(57) **CLAIM**

The ornamental design for the chair, as shown.

DESCRIPTION

FIG. 1 is a top perspective view of a chair embodying the present invention;

FIG. 2 is a front perspective view of the chair;

FIG. 3 is a rear perspective view of the chair;

FIG. 4 is a front elevational view of the chair;

FIG. 5 is a rear elevational view of the chair;

FIG. 6 is a first side elevational view of the chair;

FIG. 7 is a second side elevational view of the chair;

FIG. 8 is a top plan view of the chair; and,

FIG. 9 is a bottom plan view of the chair.
